UNITED STATES PATENT OFFICE

BAYARD E. RICHARDSON, OF GRAND RAPIDS, MICHIGAN

WOOD DESK CONSTRUCTION

Application filed March 17, 1930. Serial No. 436,377.

This invention relates to desk structures and is particularly concerned with a novel and very practical desk structure wherein various units of the desk may be made up in stock and the same assembled readily at any time to provide the complete desk. The desk construction is largely of wood and many different designs can be made, using the unit construction method of making the desk, as will appear on understanding of the invention had from the following description taken in connection with the accompanying drawings, in which,

Fig. 1 is a front elevation of a desk as made in accordance with my invention.

Fig. 2 is a fragmentary enlarged horizontal section through one side of the desk.

Figs. 3 and 4 are vertical sections taken substantially on the planes of lines 3—3 and 4—4, respectively, of Fig. 2, the parts in Fig. 3 being shown in somewhat separated and disassembled relation.

Fig. 5 is a vertical section on the plane of line 5—5 of Fig. 4, and

Fig. 6 is a fragmentary front elevation showing the various units of a desk separated and disassembled.

Fig. 7 is a fragmentary sectional view of the lower rear edge of either pedestal.

Like reference characters refer to like parts in the different figures of the drawings.

In the construction, a base unit for a desk pedestal is provided including a rectangular frame 1 which has a panel bottom 2 of any suitable material such as wood or sheet metal.

The frame 1 is adapted to have its outer side edges made with any suitable design of molding and of course many and various kinds of designs can be applied for the molding at the edges of the frame.

Above the base unit a drawer holding unit is to be mounted. The drawer holding unit is made with four posts separated from each other at the four corners of the unit, as indicated at 3, and the posts, as shown in Fig. 2 in cross section, are substantially in the form of a quadrant of a circle; that is, the outer sides of the posts are curved and the other two sides lie at right angles to each other. It

is also evident that the outer curved sides of

the posts may be carved to any desired or selected design. Between the rear posts 3 a vertical panel 4 is located and jointed therewith and permanently secured to the posts by gluing or other suitable means. In practice 55 the lower edge of the panel 4 extends a short distance below the lower ends of the posts as indicated at 4a in Fig. 6. Between the front and rear posts at each side of the units are side panels 5 similarly permanently secured to the posts. A plurality of horizontal drawer guides 6 are secured to and lie along the inner side of each side of the unit and horizontal cross bars 7 lie at the front and rear of the drawer guides as shown in Fig. 2. 65 These are mounted in spaced apart relation for the slidable mounting of the drawers 8 and an upper slide 9 as is common in desk structures.

A leg 10 is used at and below each corner of the frame 1 through which a long rod 11, threaded at its upper end, is passed, the lower end of each leg 10 is covered by a cup or ferrule 12, the head of the rod 11 bearing against the bottom of the cup; and over the bottom 75 of the cup and covering said head of the rod a foot 13 of sheet metal is permanently secured by welding or spinning the same onto the lower end of the cup or ferrule 12. The rods 11 pass upwardly through openings in 80 the corners of the frame 1 and through vertical longitudinal passages in the posts 3 so that their upper ends may connect with the top which is placed over two spaced apart desk pedestals.

The top 14 is a usual construction of flat top for desks and at a plurality of points at its lower side socket members 15 are secured which have interiorly threaded vertical openings therethrough for the rods 11 to connect with, it being evident that on screwing the rods 11 at their upper ends into the sockets 15 the top is permanently secured to the desk pedestal. It will be noted that the upper ends of the posts 3 are provided with recesses 85 to fit the downwardly extending socket members 15.

A back panel 16 is in many cases used between the spaced apart desk pedestals at the rear portions of said pedestal. This panel at 100

its lower edge is connected with a lower rail or molding 17 which extends between the frames 1 near their rear ends. The molding at its underside is provided with a longitudinal slot or groove in which a rod 18 is located (see Fig. 5) the rod passing through the inner sides of the two frames 1 and equipped with a head at one end and a nut at the other to draw the parts together. The vertical edges of the panel 16, as shown in Fig. 2, are guided between the rear posts 3 and shoulders formed adjacent the rear edges of the inner sides 5 of the desk pedestals, said shoulders being provided by rabbeting away small portions of the inner sides 5 of the desk pedestals near their rear edges. The back panel, with the attached molding 17, is slid downwardly in the guide grooves thus made until the ends of the molding rail 17 come against the upper sides of the frame 1, in which position the upper edge of the panel 16 is flush with the upper end of the desk pedestals and the top may be located thereover.

In the well between the pedestals and in front of the back panel 16 a frame is disposed and located horizontally a distance below the underside of the top 14. This frame includes a back bar 19, side bars 20 and a front cross bar 21, all preferably of angle iron, the vertical flange of the front bar 21 extending downwardly and the bars being connected together at their corners by reinforcing corner plates 22. The frame is secured in place to the desk pedestal by means of bolts, shown in Fig. 2, which pass through the vertical flanges of the side bars 20 and the inner sides 5 of the pedestals. The frame serves to support and guide the usual upper drawer 23 which is located immediately below the top between the pedestals.

In Fig. 6 the various units or elements, which can be made up separately and then assembled is shown, except that one end of the desk does not appear, it, however, being the same as the one shown. The bases, the drawer units, the top, the legs and the back panel together with the rod 18 may all be separately manufactured in any desired quantity at a time thereby permitting large quantity manufacture with attendant economy. When a drawer unit is placed upon a base 1 the depending lower edge 4a of the back 4 of a drawer unit is received in a corresponding groove in the upper side of the rear member of the space 1, thereby locating the drawer units properly with respect to the base, that the rods 11 may be readily inserted through the openings in the base and in the posts 3. The panel 16 is then slid into place and the rod 18 used so as to bind the lower parts of the desk together, after which the rods 11 are connected with the sockets 15 depending from the top 14.

This makes a very practical, economical

and especially convenient way to manufacture desks with resultant economy of manufacture and with an ability to obtain many different designs of desks using the same manufacturing method. The invention has proved to be particularly satisfactory from a manufacturing standpoint. The invention is defined in the appended claims and is to be considered comprehensive of all forms of structure coming within their scope.

I claim:

1. A construction of the class described comprising, a flat base unit having a rectangular outline, a drawer unit adapted to be located above said base unit comprising four corner posts each having a single longitudinal opening therethrough, a vertical back between the back corner posts and vertical sides between the front and rear posts, a top adapted to be located over the drawer unit, supporting members one under each corner of the base unit having longitudinal openings therethrough, rods extending through said supporting members, the corner portions of the base unit and through the openings in said corner posts, and means rigidly mounted on the under side of said top with which the upper ends of the rods have detachable connection.

2. A desk structure comprising, two spaced apart pedestals each having a base unit of rectangular outline, a drawer holding unit located on and above the base, supporting members one at each corner of and below each base unit, and a top extending over the upper ends of both of said pedestals and the space between them, socket members having interiorly threaded openings secured to the underside of the top and located one over each corner of the drawer holding units, and rods passing through the supporting members, the corner portions of said base unit and said drawer holding unit of said pedestals and threading at their upper ends into said sockets.

3. A construction of the class described comprising, a flat base unit of substantially rectangular outline, supporting members one under each corner of the unit having vertical openings therethrough, said base unit likewise having vertical openings therethrough in conjunction with the openings in the supporting members, a drawer holding unit including corner posts having longitudinal vertical openings of small size entirely therethrough adapted to be placed in conjunction with the openings in the base member, said corner posts at their upper ends having recesses formed therein, a top located over the upper end of the drawer unit, sockets secured to the underside of the top seating in said recesses to properly locate the top on and above the drawer unit, said sockets having interiorly threaded openings, and rods extending upwardly through the supporting

members, base unit and corner posts and threaded at their upper ends to make detachable connection with said sockets, said rods snugly engaging the openings in the corner posts.

- 5 4. A construction containing the elements in combination defined in claim 3, said base unit at its upper side and adjacent its rear edge having an elongated groove therein, and said drawer unit having a back between 10 its rear posts the lower edge of which extends below the lower ends of said posts to be received in said groove and thereby locate the drawer unit on the base with the openings in 15 the posts and in said base in vertical alignment.

In testimony whereof I affix my signature.
BAYARD E. RICHARDSON.
